TUFTING MACHINE HOOK

Randel P. Smith and James R. Collier, Chattanooga, Tenn., assignors to The Singer Company, New York, N.Y.

Filed Mar. 8, 1972, Ser. No. 232,986

Term of patent 14 years

Int. Cl. D15—06

U.S. Cl. D92—15

Fig. 3

Fig. 4

FIG. 1 is an edge view of a tufting machine hook showing our new design;

FIG. 2 is a side elevational view of the design;

FIG. 3 is a top plan view thereof;

FIG. 4 is a bottom plan view;

FIG. 5 is a view of the edge opposite that shown in FIG. 1;

FIG. 6 is an elevational view of the side opposite that shown in FIG. 2;

FIG. 7 is a perspective view of the side shown in FIG. 2;

FIG. 8 is a perspective view of the side shown in FIG. 6.

We claim:

The ornamental design for tufting machine hook, as shown.
